UNITED STATES PATENT OFFICE.

ERNST HAAGN, OF HANAU, GERMANY, ASSIGNOR TO THE FIRM OF W. C. HERAEUS, OF HANAU, GERMANY.

BODY TO BE HEATED ELECTRICALLY.

No. 847,665.

Specification of Letters Patent.

Patented March 12, 1907.

Application filed March 16, 1906. Serial No. 306,437.

To all whom it may concern:

Be it known that I, ERNST HAAGN, a subject of the German Emperor, and a resident of Hanau, Germany, have invented certain new and useful Improvements in Bodies to be Heated Electrically, of which the following is a specification.

Crucibles, boxes, muffles, plates, and other bodies adapted to be heated electrically are known in which the resistances are embedded in the walls. To insure a uniform load of the resistances, and thereby to lengthen the life of the said bodies, it is necessary that the resistances should be united with the body as carefully and as reliably as possible. This, however, can be effected only with difficulty, more particularly in case the bodies are small and the resistances require to be made of wire in view of the usual pressures of the current. In some cases this was effected in the manner that the wire was spirally wound on a tube of porcelain, fire-clay, or other fire-proof material by means of a lathe, or it was placed in a spiral groove on the tube, after which a paste was applied to the wire-covered surface and then the whole body was enameled. In other cases the wire was spirally wound, then the wire spiral so formed was introduced into a tube and a paste was applied to the inside of the latter to cover the wire. Both methods presented, however, the heavy defect that during the burning operation the paste will contract much more than the tube and is therefore liable to tearing or getting fractured, and in any case it will but imperfectly unite with the wires and the tube. The second method is also only possible if the wire employed be very thick, which, however, cannot be employed particularly in case of platinum wire on account of the high price of the platinum. Both methods are quite useless if plates, muffles, and boxes were to be provided with wires embedded in them. A third method, described in the United States Patent No. 688,170, is as follows: The wire is spirally wound on a core and a paste is applied to the outside. After the paste has hardened the core is removed and a paste is applied to the inside of the body so formed. This method is, however, only possible with very thick wire and is not suitable for all the shapes of the bodies to be heated electrically. My invention relates to a method which

renders it possible to produce in a simple and easy manner crucibles, boxes, muffles, plates, and other bodies almost of all possible shapes in which even very thin platinum wire is safely embedded.

In the accompanying drawing, Figure 1 is a vertical section of a crucible embodying the invention. Fig. 2 is a vertical section of a crucible and form for making it. Fig. 3 is a vertical section of a modification of the invention.

The new method is as follows: For producing a crucible *c*, say of the shape shown in a vertical section at Fig. 1, a form 1 of a corresponding shape (see Fig. 2) and preferably provided with a knob or handle 2 is covered up to its neck with a fabric or net of organic fibers tightened on it or sewed together, or a knitted stocking 3 of organic material may be drawn over the form 1 and may be secured on it by means of twine or the like tightened round its neck. Next a platinum wire 4 is wound spirally, as shown, or placed in a zig-zag line on the cover 3, and is thereon sewed with thread or yarn 5. A form 6, provided with a hole 10 for the wire 4, may be internally lined with a fireproof insulating material 7—such as clay, porcelain, fire-clay, or the like—and the form 1 covered with the fabric 3, and the platinum wire may be pressed into the material 7, so that the latter fills up the space between the two forms 1 and 2, or the insulating material 7 may be formed or cast on the form 1 in the form 6. When the material 7 has hardened by drying, the fabric 3 or the like is cut through around the edge of the material 7 and the internal form 1 with the upper part of the fabric 3 is withdrawn, so that the platinum wire 4 with the lower part of the fabric 3 or the like is left behind in the body 7 now formed. Then the external form 6 is in any known manner removed from the body 7. The latter is thereupon a little heated, so as to destroy the organic fabric 3 or the like by burning it. The body is now internally lined in any known manner with the same insulating material, so as to form the crucible. (Shown at Fig. 1.) Where so preferred, this crucible may be enameled. At last the crucible is finished in the usual manner by burning it at a high temperature, when it will be ready for use. The forms 1 and 2 may be of wood,

metal, or any other suitable material. Of course the platinum wire 4 may be replaced by a thin strip of platinum, which is spirally wound or placed in a zigzag line the same as before, if so desired. For larger vessels the wire 4 is preferably replaced by a wire net. Vessels of any other shape may be produced in the manner described above. Other bodies adapted to be heated electrically may 10 be produced in a similar manner.

What I claim as my invention, and desire to secure by Letters Patent, is—

1. The herein-described method of producing bodies to be heated electrically, which consists in securing a resistance in the desired position by means of organic matter, applying a layer of fireproof insulating material to the one side of the resistance, allowing this layer to harden, heating it a little to 20 destroy the organic matter, applying a second layer of fireproof insulating material to the other side of the resistance, allowing the second layer to harden, and finishing the body by burning it at a high temperature.
2. The herein-described method of producing vessels to be heated electrically, which consists in covering an internal form with a fabric of organic material, securing a resistance (wire, strip or wire net) in the desired position on the fabric by sewing it thereon with yarn of organic fiber, introducing the internal form with the fabric and the resistance into an external form, filling up the space between them with a fireproof insulating material, allowing the latter to 30 harden, cutting off the fabric above the external form, withdrawing the internal form with the rest of fabric, removing the external form, heating a little the vessel so formed to 40 destroy the organic matter, applying a layer of fireproof insulating material to the inside of the vessel, allowing this second layer to

harden, and finishing the body by burning it at a high temperature.

3. The herein-described method of producing bodies to be heated electrically, which consists in securing a resistance in the desired position by means of organic matter, applying a layer of fireproof insulating material to the one side of the resistance, allowing 45 this layer to harden, heating it a little to destroy the organic matter, applying a second layer of fireproof insulating material to the other side of the resistance, allowing the second layer to harden, burning the body at a 50 high temperature, and enameling it.

4. The herein-described method of producing vessels to be heated electrically, which consists in covering an internal form with a fabric of organic material, securing a 6c resistance (wire, strip or wire net) in the desired position on the fabric by sewing it thereon with yarn of organic fiber, introducing the internal form with the fabric and the resistance into an external form, filling up 65 the space between them with a fireproof insulating material, allowing the latter to harden, cutting off the fabric above the external form, withdrawing the internal form with the rest of fabric, removing the external 70 form, heating a little the vessel so formed to destroy the organic matter, applying a layer of fireproof insulating material to the inside of the vessel, allowing this second layer to harden, burning the body at a high temperature, and enameling it.

In testimony whereof I have signed my name to this specification in the presence of two subscribing witnesses.

ERNST HAAGN.
